(57) **CLAIM**

The ornamental design for a vehicle brush and grill guard
winch mounting unit, as shown and described.

DESCRIPTION

FIG. 1 is a front perspective view of a winch mounting system
and vehicle brush and grille guards;

FIG. 2 is a front view thereof;

FIG. 3 is a top view thereof;

FIG. 4 is a right side view thereof (the left side view is a mirror
image of the right side view);

FIG. 5 is a front perspective view of a second embodiment of
a winch mounting system and vehicle grille guard;

FIG. 6 is a front view thereof;

FIG. 7 is a top view thereof;

FIG. 8 is a right side view thereof (the left side view is a mirror
image of the right side view);

FIG. 9 is a front perspective view of a third embodiment of a
winch mounting system;

FIG. 10 is a front view thereof;

FIG. 11 is a top view thereof; and,

FIG. 12 is a right side view thereof (the left side view is a mirror
image of the right side view).

The broken lines shown are for illustrative purposes only and
do not form part of the claimed invention.

The rear and bottom views are non-ornamental.
